SHOWER HEAD BRUSH

Claude F. Cassius, St. Louis, Mo.

Application September 6, 1934, Serial No. 742,898

2 Claims. (Cl. 15—165)

This invention relates to new and useful improvements in brushes for shower heads.

In use, the inner side of the perforated plate of the shower head becomes covered with a deposit or scale which closes the apertures in said plate. Therefore, frequent cleaning of the shower heads is necessary to remove this scale and keep the apertures in the shower head open. The usual practice is to remove the perforate plate which is generally screw-threaded on the head and to scrape off the scale from said plate. However, the removal of the plate generally destroys the rubber gasket which is used to provide a water-tight joint between the plate and the head and thus a new gasket is required every time the plate is removed. Where a large number of shower heads are used, as in Y. M. C. A. buildings and in various clubs, the replacement of the gaskets is a considerable expense and the time required to disassemble and clean each shower head is considerable and increases the cost of maintenance.

The objects of the present invention are to provide a brush which can be easily inserted into the shower head through the neck portion thereof and which can be manipulated to remove the scale from the inner side of the perforate plate without the necessity of removing the latter from the head.

Other objects of the invention are to provide a brush for shower heads, which brush consists of two sections hinged together and so constructed that the bristle section of said brush can be inserted into said shower head and placed in a position at right angle to the shank section with the bristles presented downwardly against the inner side of the shower head plate whereby, upon the manipulation of said shank section, the bristle section is operated over the inner surface of said plate to remove the scale deposit therefrom.

Additional objects of the invention are to provide a brush of the character described which is of simple but durable construction, is highly efficient in performing its intended functions, and can be economically manufactured.

With these and other objects in view, my invention consists in certain novel features of construction and arrangement of parts, hereinafter more fully described and claimed, and illustrated in the accompanying drawing, in which—

Figure 1 is a vertical cross section through a shower head showing my improved brush in position therein.

Figure 2 is a horizontal cross section taken on line 2—2 of Figure 1.

Figure 3 is a horizontal cross section taken on line 3—3 of Figure 1.

Figure 4 is an enlarged detail cross section of the lower end of said brush and showing in dotted lines the position of the bristle section when not in use.

Figure 5 is a fragmental detail view showing a modified form of the brush.

Figure 6 is another detail view of same.

Figure 7 is a fragmental detail cross section showing a modified form of a plug.

Referring by numerals to the accompanying drawing, 10 indicates a shower head, which consists of two pieces, namely, a body portion 11 and a perforate plate 12. The body portion 11 is bell-shaped in cross section and has a restricted end or neck portion, as indicated at 14, provided with an internal screw head 15 for attachment to a suitable pipe connection (not shown). The opposite or flared-out end 16 of said body portion 11 is provided with an external screw-thread 17.

The perforate plate 12 is provided with an upwardly presented annular flange 18 which is formed with an internal screw-thread 19 for engaging the externally screw-threaded portion 17 of body portion 11. A gasket 20 of rubber is preferably used between the end 16 and plate 12 to insure a water-tight joint.

Preferably the outer shape of the neck portion 14 is non-circular in cross section to facilitate the securement to the pipe connection.

When the shower head is in use, the inner side of plate 12 becomes coated with scale or incrustations, due to the minerals contained in the water and to the action of heat when hot water is used. The result is that most of the perforations in plate 12 soon become closed, thereby rendering the shower head unfit for use. As stated before, heretofore it has been necessary to remove plate 12 in order to scrape off the scale from the inner surface thereof.

The invention consists of a brush 21 so constructed that it can be readily inserted into the shower head through the neck portion 14, whereupon the bristle section can be positioned against the inner surface of said plate and manipulated to loosen the scale without disassembling the plate from its position on the head.

This brush comprises a shank section 22 and a bristle section 24. The length of the bristle section is substantially equivalent to the inner radius of plate 12. The two sections 22 and 24 are hingedly connected together, as indicated at 55

25, in such a manner that the bristle section can move into a position substantially at right angle to the shank section 22 with the bristles 26 presented downwardly against the plate 12.

5 Stop means are provided to prevent the bristle section 24 from moving upwardly beyond its horizontal or right-angled position so that said bristles 26 can be pressed against the inner surface of the plate by applying pressure to the 10 shank section 22.

In the preferred form, this stop means consists of a square shoulder 27 formed on the end of shank section 22 by ears 28. This shoulder is engaged by the upper face 29 of the bristle section 24 near the hinged end thereof so that the upward movement of said bristle section is limited to right-angled position.

A collar 30 is adjustably fixed on the shank portion 22 by means of a set screw 31. This 20 collar has an outside diameter slightly less than the diameter of the internally screw-threaded portion 15 of the neck end 14 so as to fit loosely thereinto and form a bearing for the brush when actuated. The upper end of this collar is formed 25 with a flange 32 which, when the collar is properly adjusted, bears against the outer end of the neck portion 14 when the brush section 24 occupies horizontal position with the bristles thereof pressed against the inner surface of plate 12.

30 The shank portion 22 terminates in a handle 34 by means of which the brushes can be manipulated. The forward end of the brush section 24 is tapered, as indicated at 24a, to provide clearance between the lower end of the body 35 portion 11 and said bristle section and the bristles at said forward end extend forwardly and obliquely, as indicated at 26a so as to clean the plate 12 adjacent to the lower end of the body portion 11.

40 In order to prevent the brush 24 from turning in the shower head 10, in a direction opposite to that shown, the pivotal end of brush 24 has one corner finished square as indicated at 24b. This corner engages the square shoulder 27 of shank 45 22 when said brush is disposed coaxially with said shank, as shown in dot-and-dash lines in Figure 4, and prevents said brush from moving past this position.

In the modified form shown in Figures 5 and 6, 50 the shank portion 35 is formed near its lower end with a lateral lug 36 which bears against the upper face of brush 37 when the latter occupies horizontal position. Thus pressure can be applied to the brush through the shank with minimum danger of injury to the pivot. Preferably, this lug has formed integral therewith a pair of ears 38 which extend downward to each side of the brush and relieve the pivot of lateral strain.

In the modified form shown in Figure 7, a plug 60 32a is provided having an externally screw-threaded portion 39 for engagement with the internally threaded portion 15 of member 13.

Shank 40 is provided with a collar 41 adjustably fixed thereon below plug 32a.

A coiled expansion spring 42 is interposed on said shank between said plug 32a and collar 41. When said plug is secured in position in the 5 shower head, spring 42 is compressed, thereby automatically placing the brush under the required pressure against the perforate plate 12.

My improved shower head brush is of simple construction, can be easily applied in position 10 and operated, and is highly efficient in performing its intended functions.

While I have disclosed herein the preferred forms of my invention, it is to be understood that other changes can be made in the brush without 15 departing from the spirit of my invention.

I claim:

1. In a brush for cleaning shower heads, the combination of a shank section having a handle at one end, a bristle section pivotally connected 20 at one end to the other end of said shank section and movable into a radial position relative thereto, means on the interengaged ends of said section for preventing said bristle section from moving past the radial position, a collar adjustably mounted on said shank section, said collar having a reduced portion adapted to fit within the opening of the neck portion of a shower head and having an enlargement adapted to bear 25 against the outer end of said neck portion where- 30 by said collar forms a bearing for said shank section, and means for securing said collar in adjusted position on said shank section, whereby the length of the shank section insertable into the shower head can be regulated. 35

2. In a brush for cleaning the interior of shower heads, the combination of a shank section having a handle at one end and having an apertured end at the other end, there being a horizontal shoulder formed on said shank section in spaced relation with said aperture, a bristle section provided with bristles on one side and having one end apertured and pivotally connected to the apertured end of said shank section, one corner of said apertured end of said bristle section being rounded out and the other formed square whereby said bristle section is movable from a vertical position into a radial and horizontal position in one direction only and is held against movement in opposite direction by the engagement of said square corner with said horizontal shoulder, and a collar adjustably fixed on said shank section in spaced relation with said bristle section, said collar being provided with a reduced portion extending into the internally threaded 45 interior of said neck portion of said shower head, said collar having a radial flange adapted to bear against the end of said ring and form a bearing for said brush and limit the movement of said shank into said shower head. 50 55

CLAUDE F. CASSIUS.
